UNITED STATES PATENT OFFICE.

BERNARD R. GUION, OF NEW YORK, N. Y., ASSIGNOR OF TWO-THIRDS
TO ALEXANDER LUTZ, OF SAME PLACE, AND JAMES E. WALSH, OF
DANBURY, CONNECTICUT.

SANITARY RECEIVING-BASIN.

SPECIFICATION forming part of Letters Patent No. 658,639, dated September 25, 1900.

Application filed November 24, 1899. Serial No. 738,169. (No model.)

To all whom it may concern:

Be it known that I, BERNARD R. GUION, a citizen of the United States, and a resident of New York city, in the county of New York and State of New York, have invented certain new and useful Improvements in Sanitary Receiving-Basins, of which the following is a specification.

This invention relates to new, useful, and sanitary improvements in receiving or catch basins for cities and towns to receive and discharge the surface-water from streets into the sewers, also to be connected with the drainage from factories and slaughter-houses independent of the discharges from water-closets and urinals.

The common form of receiving or catch basins now in use for street service in cities and towns is objectionable for numerous reasons. The first is the inability of said basins to properly retain the sediment in the surface-water from said streets and prevent it from being carried off with the sewers, where it lodges, thus eventually clogging up the same; second, that during a dry spell a large volume of water is held in said basin, becoming more and more foul every day, throwing off foul and offensive gases. Third, the pressure of this large body of foul water is furthermore objectionable when the basin is to be cleaned, for the reason that said water has to be removed and deposited upon the street, where it is usually retained in a pool until the heavier deposits are removed from the basin, after which said water is permitted to again run back into the basin. This form of procedure is objectionable and a nuisance, as foul and obnoxious gases arise from the foul water. Fourth, when the sediment has accumulated in said basin above the bottom of the trap-stone the surface-water from the streets cannot flow into the sewers. Consequently the streets and sometimes the cellars of houses are flooded. A further and material objection to the present form of construction of said basins is in the manner the heavy accumulations or deposits have to be removed. It is first necessary to dip out the water and pool it, as above set forth, after which men are sent into the basin with shov-

els and buckets, and the mud, sand, and heavy deposits are taken out in a way which is very slow and disagreeable, especially since after the water, the mud, sand, and heavy deposits referred to have been removed from below the bottom of trap-stone the outlet to the sewer is opened and its gases permitted to escape.

My invention is designed with especial regard to the objections above noted; and it is the object of my improvement to first provide a receiving-basin which is a sanitary device of simple and durable construction; second, to arrange so as to permit of the convenient and ready removal of the heavy deposits and without the necessity of handling any of the water used for trapping the sewer, to prevent the possibility of flooding the streets and cellars of houses, to insure the purification of the water and its separation from the deposits and impurities as they pass through the basin, and, finally, in providing an automatic siphoning device which operates to take off the large volume of water and insure the detention of sufficient water within the basin to at all times form a trap for the sewer-pipe; also, that there will be no necessity of allowing the matter to remain in the basin and become foul and obnoxious, as it can be changed at any time in a few moments; also, that the appliance can be put in any receiving-basin as now constructed in any city or town, without the necessity of changing the brick masonry or the head or gutter stone, at a small cost.

With the above objects in view my invention consists in the novel construction and combination of parts set forth in the accompanying two sheets of drawings, forming a part of this specification, upon which similar characters of reference denote like or corresponding parts throughout the several figures, and of which—

Figure 1 shows a central vertical longitudinal section through my improved receiving basin, the cover being detached and the removable basket hoisted out for emptying. Fig. 2 is a similar sectional view with the basket in place, the basin closed, and ready for service. Fig. 3 shows a slightly-modified

form of basin, the same being adapted for private use, such as factories, &c. Fig. 4 is a cross-section taken at a right angle to Figs. 1, 2, and 3 and on line 4 4 of Fig. 1, looking 5 in the direction of the opening. Fig. 5 is a similar cross-sectional view showing the screen contracted to form a smaller outlet. Fig. 6 is a sectional plan on line 6 6 of Fig. 1; and Fig. 7 shows a similar sectional plan of 10 a round basin instead of a square, as illustrated in the preceding figures.

Referring in detail to the characters of reference marked upon the drawings, A indicates the main compartment of the basin, 15 B the cap-stone, and C the cover.

D represents the inlet from the street, of which E shows the curb and F the gutter lines, respectively.

My basin may be formed of any preferred 20 shape—such as square, round, or hexagon—and is divided by means of a vertical screen-wall G, thus dividing the basin into a large and small compartment A and H. Within the large or main compartment I locate a 25 receiving-basket I, which is of special construction and is designed to catch the flow of water as it pours in through the opening D from the street. This basket is formed of either perforated sheet-metal or wire screen, 30 which construction insures the detention therein of all the solid matter which comes in with the flow of water and permits of the free exit of said water from said basket. The basket is provided with a chain-handle K, by 35 means of which it is engaged for hoisting from the basin. In practice this basket is raised from the basin by means of a suitable derrick, which is so arranged that the basket may be elevated above a cart, into which the 40 contents of said basket are deposited and carted off. I further provide the basket with a detachable bottom, whereby the deposits above referred to may be quickly removed. This detachable bottom is formed of solid 45 doors L L, which are hinged at either side and overlap at the middle in a manner to be secured by suitable catch M, as shown.

The compartment H, before mentioned, 50 may be built on as an addition to the main basin or may be produced by dividing a large receptacle, as shown in my drawings. As before stated, the two compartments are divided with a screen G, which may constitute the entire wall, as shown in Fig. 4, or it may 55 be of reduced size and set into a wall of masonry, as shown in Fig. 5. The upper part of this screen-wall contains a door N, as shown, whereby access may be had to the small chamber of the basin for cleaning or 60 other purposes. The bottom of this small compartment is below that of the main or larger one, thus forming a deeper receptacle and one which will permit of the drainage from said larger receptacle. From the bottom 65 of this small receptacle I make my pipe connection for the street-sewer, which connection consists of a pipe O, having an elbow set in the

edge of the wall and having a vertical inner end P and a deflected outer portion Q. The inner end of this pipe is disposed adjacent to 70 the bottom of the chamber in a manner to drain the water therefrom after the siphon has once been started. Around this pipe and within the small chamber I pack a quantity 75 of gravel R of suitable size, through which the water flows, in addition to the screen-partition G, from the main basin, and it strains down through said gravel and fills up around the mouth of the pipe R.

From the foregoing description it will be 80 apparent that the action of my improved basin is as follows: The water when flowing in from the streets is first deposited in the basket, where it leaves all of the solid matter. From this basket the liquid runs out 85 into the smaller receptacle through the screen-partition and the gravel contained within the smaller compartment until the latter is filled up and overflows out through the outlet-pipe O, which flow of water forms a siphon from 90 the basin to the street-sewer. This siphon once started will continue to flow until the water is drawn entirely out of the large receptacle and down to the bottom of the smaller one, whereby the seal is broken and air is let 95 into the suction-pipe or siphon. The moment the seal is broken the siphon stops 100 flowing. The column of water in said siphon falls around the mouth of the pipe or siphon, thus forming a seal for the same, and prevents the sewer-gas from escaping from the sewer.

From the above operation it will be seen that the heavy and coarse substances which are present in the water are lodged in the 105 basket and the water drained from them, thus leaving said coarse deposits at all times ready to be removed without interference by the presence of water.

Having thus described my invention, what 110 I claim, and desire to secure by Letters Patent, is—

1. In a sanitary receiving-basin the combination of the main compartment, an adjacent compartment separated therefrom by means 115 of a screening device and its bottom below the level of the main compartment in a manner to drain the same, a door located in said screening device, a siphoning device leading from said smaller compartment and adapted 120 to automatically drain the water from the basin, a filling of gravel or like material placed around said pipe, a basket suspended within the main compartment and means to permit of said basket being hoisted therefrom.

2. The combination in a receiving-basin of the main compartment, a basket located therein, a collapsible bottom for said basket and means for removing the same from the 130 compartment for discharging its contents, a secondary compartment having its bottom below that of the first compartment in a manner to drain the same, a screen separating

the same, a door located in said screen a drain-pipe leading from the compartment in said second compartment and having its inlet below the level of the first compartment in a 5 manner to siphon the water therefrom.

3. A sanitary receiving-basin comprising a main compartment, a basket suspended therein and adapted to receive the deposits and drain the same, means for removing the basket from the compartment, collapsible doors in the bottom of the basket whereby the contents may be discharged, a second compartment adjacent to the first and whose

bottom is below that of the first compartment, a filling of gravel in said second compartment, a door leading from one to the other, a siphoning-pipe leading from the second, and lower compartment, whereby the device may be drained. 15

Signed in the city, county, and State of New York this 31st day of October, A. D. 1899.
